UNITED STATES PATENT OFFICE.

ELIAS C. ATKINS, OF INDIANAPOLIS, INDIANA, AND NATE H. ROBERTS, OF PASADENA, CALIFORNIA.

ROTARY PLOW.

SPECIFICATION forming part of Letters Patent No. 543,118, dated July 23, 1895.

Application filed December 8, 1894. Serial No. 381,013. (No model.)

To all whom it may concern:

Be it known that we, ELIAS C. ATKINS, residing at Indianapolis, in the county of Marion and State of Indiana, and NATE H. ROBERTS, residing at Pasadena, in the county of Los Angeles and State of California, citizens of the United States, have invented certain new and useful Improvements in Rotary Plows, of which the following is a specification.

Our present invention consists in certain improvements in details of construction and arrangements of parts upon that general class or variety of rotary plows shown and described in the application of Nate H. Roberts, Serial No. 508,421, filed April 21, 1894.

Such improvements will be first fully described, and then particularly pointed out in the claims.

Referring to the accompanying drawings, which are made a part hereof, and on which similar letters of reference indicate similar parts, Figure 1 is a top or plan view, with the seat removed and its position shown in dotted lines, of a rotary plow embodying our said invention; Fig. 2, a side elevation of the same; Fig. 3, a detail top or plan view on a somewhat enlarged scale, the plowing-disk and scraper-arm bearing and support being shown in section; Fig. 4, a perspective view of the scraper and scraper-arm separately; Fig. 5, a detail view of the caster-wheel at the rear of the plow and its connections; Fig. 6, a rear elevation of the same, and Fig. 7 a detail view showing the particular form of the clevis at the front end.

As above stated, our invention is in many particulars similar to that shown in the application, Serial No. 508,421, referred to. We have, however, illustrated a plow for very heavy work and provided with a multiplicity of plowing-disks, which has necessitated the same rearrangement of parts and the providing of additional means to resist side draft.

In the drawings, the portions marked A represent the axle; B, the main frame; C, the plowing-disks; D, the land-wheel; E, the caster-wheel; F and G, staggered guide-wheels; H, a stop by which the movement of the guide-wheel G is in a measure controlled; I, weed-hooks, and J scrapers for the disks.

The axle A is of a usual and well-known form and carries the spindles for the wheels D and F. The spindle for the wheel D is on an arm A', which is capable of being rotated on the shaft, and the wheel thus positioned higher or lower relatively to the remainder of the machine; and said arm is operated by the usual lever and latch arrangement A''. The spindle for the wheel F is mounted in the vertically-sliding bearing A'', and is elevated or depressed by the usual lever and latch arrangement A'''.

The main portion B of the frame, like that shown in the application, Serial No. 508,421, consists of an I-beam bent at an angle. It is mounted in a cast bolster A' on the axle A, which bolster is also extended out and carries the lever H', and is secured in a seat in said bolster by the bolts a'. Said beam is provided with as many arms B' B'' as there are plowing-disks. Four such arms are shown in the drawings, arranged as we have planned for a large plow with this number of plowing-disks. It will be observed that one of these arms B' is larger and of a different character from the arms B''. The same plow can be transformed into a smaller plow by removing one or two of the arms B', together with the plowing-disks carried thereby, and moving the arms B' up to the corresponding location, thus reducing the size of the plow to a one-disk, two-disk, or three-disk plow without other change; and, of course, by extending the beam B additional arms and disks can be provided sufficient to suit any reasonable requirement.

A tool-box T is mounted near the forward end of the beam B, and on its extreme forward end is a draft attachment, consisting of a horizontally-positioned T-shaped head B', having numerous holes, and a vertically-positioned T-shaped head B'', secured thereto and also having several holes to which the clevis B' may be attached. This is illustrated in Figs. 1 and 7, and by this arrangement a great range of adjustment of the two devices is provided for.

The plowing-disks C are of the same form shown in previous patents and applications for patents, and are mounted on the arms B' and B'' in a similar manner to that indicated in said

patents and applications. The wheel D is also of the usual form. It is provided, however, with a scraper D' by which the earth which may adhere thereto is effectually removed.

The caster-wheel E is mounted in a housing E', the stem E² of which passes up through a bearing E³, which in turn is mounted to slide vertically in a bearing E⁴ on the beam 10 B, being secured thereto by a bolt b². The stem E² has collars e² e³ thereon on each side of the bearing E³, and its vertical position can be adjusted by adjusting said collars. Further adjustment can be made by sliding 15 the bearing E³ on the bearing E⁴. A long adjustment is thus provided for without excessive length of the stem E². Near this point on the frame B is secured a weight-stem B⁴, on which may be arranged weights b⁴ of suitable number and character.

The staggered guide-wheel F is also similar to those shown in former patents and applications. It is provided with a scraper F', by which adhering earth is removed from its surface. The staggered guide-wheel G in itself is also similar in form and arrangement to the corresponding guide-wheels of the former 25 patents and applications. It has a scraper G', by which adhering earth may be removed from its surface. It is mounted upon a spindle forming part of a bent shaft G², which, as indicated by the dotted and full lines in Fig. 2, embodies a single rod forming a vertical pivot upon which the whole structure swings, 30 a horizontal arm, and an inclined spindle for the wheel. Its vertical portion carries collars g g', which are arranged in the two sides of that portion of the arm B' through which it passes and whereby it is carried. Obviously 35 by adjusting these collars the vertical position of the staggered guide-wheel G can be varied. At that point where it bends from the horizontal to the inclined position, for the purpose of forming a spindle for the wheel G, there is cast thereon an angle-block G³, which 40 constitutes a shoulder for the wheel G to bear against, a point of attachment for the scraper arm G', and a base for the weight-supporting pin G⁴, on which weights g⁴ of such size and 45 number as the work may require are mounted. The collar g' is provided with or embodies an extension and thus forms, also, a stop-arm by which the arm G², and with it the wheel G, are prevented from swinging in one direction 50 while the plow is in operation, while they are free to swing in the other direction. Said wheel G thus performs its function as the guide-wheel for resisting the side draft of the plow, and at the same time is free to swing 55 in the other direction in turning the plow.

The stop H is pivoted at h and receives the pressure from the stop-arm extending out from the collar g'. It is operated by a connecting-rod H', which extends forward and 60 connects to the lever H². As will be observed by an inspection of Fig. 2, the rod H' passes over the top of the stop H, which is in itself

as thick or a little thicker than the arm on the collar g'. The stop H may be thus moved back so that it will rest against the projection 70 b' on the arm B, and the arm on the collar G' will be free to swing around underneath the rod H'. This device is operated when it is desired to swing the plow in the opposite direction from that in which the wheel G can 75 swing freely when the parts are in their normal position. After the turning has been effected by throwing the lever H² forward the stop H is forced back to its position, first striking in its movement the inner curved 80 surface of the arm extending out from the collar g', and, continuing its contact, forces said arm and the arm G', carrying the wheel G, back into its proper place, as will be readily understood. The lever H² is provided with 85 the ordinary latch h², by which it is held to adjusted position.

The weed-hooks I are secured by bolts i to the main beam B of the frame and extend under said frame across in front of the plowing 90 disks C and are curved inwardly to approximately the contour of the inner surface of said plowing-disks until they reach a point nearly central thereof, whence they bend outwardly across the path of travel of the plow. By 95 this peculiar conformation and arrangement they effectually drag down all the weeds in the path of the plow into position to be covered by the dirt thrown up by the plowing-disks. We have discovered by experiment 100 that it is essential with a rotary-disk plow that these weed-hooks should be bent into near the inner surface of the plowing-disks in order to operate effectually.

The scrapers J are pivotally mounted by 105 means of their stems j in arms J', which arms, as best shown in Figs. 3 and 4, are secured to projections b³ on the arms B' B² of the frame by clamping-bolts j'. As also shown in said figures, the surfaces of said arm and said projection which come in contact are concave 110 and convex, respectively, thus forming a knuckle-joint which permits of any desired adjustment. The vertical adjustment is provided for by moving the arm on the bolt j', 115 and it can be held to adjusted position by means of the adjusting-screws j', which pass through a projecting ear on the arm J' and rest against the upper surface of the beam B or arm B².

Having thus fully described our said invention, what we claim as new, and desire to secure by Letters Patent, is—

1. The combination, in a rotary plow, of the axle A, the bolster A' thereon provided with 120 an annular recess to receive the beam, the bent frame beam B fitted into said recess, and bolts a³ by which the axle, bolster and beam are united together, all substantially as shown and described.

2. The combination, in a rotary plow, with 125 the frame, of a caster wheel E, a housing E' therefor having a stem E², a bearing E³ through which said stem passes, said stem be-

ing provided with adjustable collars e^2 e^3 alongside of said bearing, and a bearing B^3 on the frame B to which said bearing E^3 is adjustably secured by bolts b^3 , substantially as shown and described.

3. The combination, in a rotary plow, with the frame and the plowing disks, of a staggered guide wheel G, a bent shaft G^2 , which in itself embodies a vertical pivot, a horizontal arm and an inclined spindle for the wheel, and provided at the point where it is bent with an angle block G^3 constituting a shoulder for the guide wheel, and the base for a weight-supporting pin, said weight-supporting pin and the weights thereon, substantially as set forth.

4. The combination, in a rotary plow, with the frame and plowing disks, of a staggered guide wheel mounted on a swinging arm which swinging arm has a vertical portion forming a pivot, a stop arm secured to said vertical portion, a pivoted stop II secured to the frame in front of said stop-arm, and a connecting rod H' and a lever H^3 whereby said pivoted stop is operated, substantially as shown and described.

5. The combination, in a rotary plow, with the plowing disks, of weed hooks I secured to the frame and curved inwardly to approximately the contour of the inner surfaces of the plowing disks until they reach a point nearly central the plowing disks, and bent thence outwardly across the line of travel of the plow, substantially as shown and described.

6. The combination, in a rotary plow, with the plowing disks, of weed hooks I secured to the frame in front of the plowing disks and extending transversely across in front of the plowing disks and thence back along the inner

surface thereof a certain distance and outwardly across the line of travel of the plow substantially as set forth.

7. The combination, in a rotary plow, with the plowing disks, of scrapers J mounted on arms J' , which said arms are secured to the frame by means of knuckle joints, whereby they may be adjusted in any direction desired, substantially as set forth.

8. The combination, in a rotary plow, with the plowing disks, of scrapers J having stems j which are pivotally mounted in arms J' , and said arms J' which are adjustably secured to the plow frame, substantially as set forth.

9. The combination, in a rotary plow, with the plowing disks, of the scrapers J, arms J' therefor, projections b^2 on the frame to which said arms are secured, bolts j' by which said arms are secured to said projections, ears on said arms extending above adjacent portions of the frame, and adjusting screws j^2 passing through said ears and adapted to bear on the surface of such adjacent portions, substantially as set forth.

In witness whereof I, the said ELIAS C. ATKINS, have hereunto set my hand and seal, at Indianapolis, Indiana, this 20th day of November, A. D. 1894.
